CADMIUM-FREE LOW FUSING POINT ALLOY

Albert A. Smith, Jr., Metuchen, and John L. Everhart, Linden, N. J., assignors to American Smelting and Refining Company, New York, N. Y., a corporation of New Jersey

No Drawing. Application October 7, 1950,
Serial No. 189,044

1 Claim. (Cl. 75—134)

1
This invention relates to alloys and more particularly to low fusing point alloys.

It is an object of the invention to provide cadmium-free, low melting point alloys.

In accordance with the invention, alloys are provided comprising, by weight, 32-34% Bi, 42-44% In, 7-8% Pb and 15-18% Sn, and have fusing points of approximately 59° C.

It will be observed from the compositions that these alloys do not contain cadmium and, accordingly, they are particularly suitable for certain applications as heat transfer media where cadmium would be detrimental.

What is claimed is:

Low melting point alloys composed of 32-34% Bi, 42-44% In, 7-8% Pb and 15-18% Sn. 15

ALBERT A. SMITH, JR.
JOHN L. EVERHART.
